UNITED STATES PATENT OFFICE.

CHARLES H. CLARK, OF DORMONT, PENNSYLVANIA, ASSIGNOR TO CLARK CAR COMPANY, A CORPORATION OF PENNSYLVANIA.

SIDE-DUMP CAR.

1,403,843.

Specification of Letters Patent. Patented Jan. 17, 1922.

Application filed September 28, 1918. Serial No. 256,130.

To all whom it may concern:

Be it known that I, CHARLES H. CLARK, a citizen of the United States, and a resident of Dormont, in the county of Allegheny and State of Pennsylvania, have made a new and useful invention in Side-Dump Cars, of which the following is a specification.

This invention relates to side dump cars and in this application is illustrated in connection with a car of the type disclosed in application Serial No. 124,986 filed by me and Howard L. Beach on October 11, 1916 now Patent No. 1,338,293, granted March 9, 1920.

An object of this invention is to provide a balanced rocker side dump car which will not only right itself without the application of external force but one in which the movements from dumped to upright position are so controlled that the righting is accomplished without undue shock.

A still further object is to provide a rocker side dump car in which the point of contact between the rocker and its mating rocker stand is retarded in its progression whereby the sum of the moments tending to move the car to upright position are always somewhat in excess of those opposing such movement.

A still further object is to provide in side dump cars, a form of rocker and mating rocker stand adapted to retard the acceleration of the falling load while in contact with the car whereby larger size units for standard gage railway tracks may be built without the danger of the movement of the load dragging the car with it over the dump.

These, as well as other objects which will readily appear to those skilled in this particular art, I attain in the construction described in the specification and illustrated in the drawings accompanying and forming a part of this application, and throughout which similar elements are denoted by like character.

The car selected for illustration is of the gondola class and consists of a body, sides and under-frame or draft sill. The body which carries the load is supported by bolsters located adjacent the car ends and associated with each of these is a rocker and a mating rocker stand designed to allow the car to dump toward either side of the track and to tilt the body to the desired angle from the horizontal. The sides are hinged to the body below the floor level at

intervals throughout their length and are actuated in opening and closing by mechanism connected to their lower extremities and to suitable latch shafts carried by the under-frame as in the construction of said application.

As the body proceeds to dumping position the locations and paths of the door opening mechanisms are such as to cause the mechanisms to change their relation to the body, permitting one or the other side to turn about its hinge points simultaneously with the tilting of the body, the mechanisms being arranged so that the sides swing through an angle of 90 degrees as the body swings through an angle of 40 degrees.

In this type of car the body is usually dumped by admitting air under pressure to telescopic dump cylinders located adjacent the ends of the car.

In the drawings, Figure 1 is a view in cross section of a car embodying this invention showing one of the bolsters and one of the rocker mechanisms in end elevation, Fig. 2 is a cross sectional view of said car taken at such a position as to show one set of the operating links and levers in end elevation. In both Figs. 1 and 2 the body and doors by dotted lines are shown in dumping position. Fig. 3 is an enlarged detail view of the rocker and its mating rocker stand used in the car embodying this invention. In this view the rocker stand is shown in end elevation and the rocker in sectional elevation. The position of the rocker when the car is in dumped position is also shown by dotted lines. Fig. 4 is a diagrammatic view of a car embodying this invention and indicates the retarding of the progression of the point of contact between one of the rockers and its mating rocker stand whereby the returning moments are always maintained somewhat in excess of the retarding moments.

Referring to the drawings 10 designates the longitudinal center sill of the under-frame and this extends from end to end of the car. The car body is supported adjacent each end by a bolster 11 provided at its center with a downwardly curved portion 12 to which a rocker 13 is secured. The rocker 13 is adapted to roll on and to cooperate with a rocker stand or way 14 located on the upper side of an under-frame bolster 15.

The load carrying portion of the body

consists of floor plates 16, end walls 17 and downwardly and outwardly opening longitudinal side walls or doors 18 and 19. A central I beam 20 extends from end to end 5 of the body beneath the floor plates 16.

The doors are hinged throughout their length to the body under-frame below the floor level as shown at 21.

The door on the lowering side of the body 10 is adapted to automatically open during the tilting movement and to automatically close during the righting movement. The mechanisms whereby the opening and closing is accomplished are preferably the same as 15 those illustrated and described in the application before mentioned and consist of a bell crank lever 22 fulcrumed at 23 to the under portion of the body frame. In normal position, that is with the body upright,

20 the short arm of the lever is disposed downwardly while the longer arm extends outwardly toward the door. The long arm of the bell crank by means of a link 25 is connected to an arm 24 extending downwardly 25 from the door, while the short arm of the bell crank by means of a link 26, latch pin 27 and a link 28, connects with a bracket 29 secured to center-sill 10 of the under-frame.

30 Latch hooks 30 are secured to actuating shafts 31 which extend longitudinally of the frame and are journaled in suitable bearings 32 formed in a bracket 33 secured to the under side of the center sill 10. The 35 latches when swung outwardly are adapted to engage the extremities of latch pins 27 thereby locking the car body against tilting. The latch hooks are yieldingly held in engagement with the latch pins by means 40 of a spring 35 which connects the lower ends of lever arms 36 carried by the actuating shafts.

The long arm of bell crank 22 carries an 45 abutment or stop member 37 and link 25 carries a cooperating abutment or stop member 38. When the car body is in normal or upright position these stop members abut, and the angles of their abutting faces with 50 relation to their major axes are such that pin 39, which forms the pivotal connection between the bell crank and link 25, lies below a line extending through the centers of pin 23 and a pin 40 which connects link 25 to the lower end of the door. A toggle is 55 thus produced for holding the door in closed position and the door is thus held until the toggle is broken by the upward movement of the long arm of the bell crank about pin 23.

60 When the car is to be dumped the latch hooks on the opposite side of the car to which the material is to be dumped are 65 swung to release the latch pins on that side of the car and then the body, by the body tilting means (such as telescopic air cylin-

ders not shown) is tilted to dumped position. The toggle on the rising side maintains the door on that side in closed position, links 26 and 28 being released by the latch hooks 30 are allowed to freely extend as 70 shown by dotted lines in Fig. 2 without exerting any turning force on the bell cranks of the rising side.

At the dumping side the downward tilt of the body causes bell cranks 22 on that 75 side to swing from the full line position of Fig. 2 into the dotted line position thereof, causing the door on the downward side to move through an angle of 90 degrees while the body moves through an angle of 40. 80

As clearly shown in Fig. 3, the bearing surface 41 of the rocker is formed on the arc of a circle except that at its center 42 it is flattened for a distance on each side of the center line. The rocker stand is formed 85 on each side of the center line so as to present three bearing surfaces, a center surface 43 which is horizontal, an intermediate surface 44 which stands at an angle to the center horizontal surface, and an outer surface 45 preferably parallel to the intermediate surface. An angular surface joins the outer and intermediate surfaces forming a shoulder or offset at the inner end 46 of the outer surface, up over which the rocker 90 rides as the car body is tilted. The extreme outer ends of the rocker stand are inclined toward the sides of the car thus forming a bearing surface for the lower side of the car bolsters against which they rest when 100 the body is in dumped position. The rocker stand is provided with upstanding gear teeth 47 adapted to register and mesh with openings 48 formed in the rocker. The stand also has openings 49 for the reception of teeth 50 formed on the rocker member. 105

The offset between the rocker and its mating rocker stand provided by the shoulder 46 in the stand affords means for retarding 110 the progression of the point of contact between the rocker and the rocker stand and by thus retarding the progression of said point of contact the returning moments are always maintained in excess of the retarding moments. The flattened portion 42 at the center of the rocker and the corresponding portion 43 on the stand provide that a point of support shall be maintained at a distance from the center of the car, thus 115 giving the body stability when upright, and if the car is being righted, they limit the approach of the supporting point towards the center of the car until the last degree of travel and thereby insure a maintenance 120 of the excess of the returning moments over the retarding moments.

The effect of suspending the progression of the point of contact at predetermined 125 positions on the rocker stand provides addi-

tional counter balance in the car body moments adapted to offset the retardation of the door motion moments at corresponding positions.

5 The body in moving from upright to dumped position is raised a certain distance by means of the offset raised bearing surface 45 and of course in rolling is moved a distance toward the side of dumping. By reason of this superelevated position of the body and the door on the upper side it is quite obvious that work has been done against gravity and the body and upper door therefore possess more potential energy when the 10 car is in dumped position than when it is in upright position. On the other hand the down turned side has been lowered with respect to the body and therefore possesses less potential energy in the dumped position 15 than in its upright position. By means of the system of links and levers comprising the door operating mechanism and by means of the peculiar formation of the rocker rack or stand the various parts are slightly counter-balanced in closing direction about the 20 point of contact between the rocker and the rocker stand. Since the normal distance from the point of contact to the direction of force when multiplied by that force gives 25 the moment of the force about the point of contact it follows that the moments of the closed side and body (without sides) tend to produce a counter-clockwise rotation of the body and are termed returning moments, 30 while the moments of the down turned side and those of the latch hook links tend to produce a clockwise rotation and are termed retarding moments. In any position of dump from 40 to zero degree position the 35 sum of all the returning moments on account of the peculiar contour of the rocker stand are greater than the sum of all the retarding moments so that the body after dumping will right itself without the aid of any external force and do this smoothly and without serious shock or injury to the car or mechanisms.

45 The flat portion at the center of the rocker prevents the point of contact between the 50 rocker and the rocker stand from approaching the center line closer than the distance from the center line to the edge of the flat part, and the impulse of the returning moment is increased by this retardation and is 55 used to throw the latches and securely lock the car in upright position.

60 The interengaging gear teeth and pockets on the rocker and rocker stand maintain the relative longitudinal and lateral alinement of the body and under-frame.

65 In the diagrammatic illustration shown in Fig. 4 the paths of the center of gravity are shown by the lines connecting the various positions, that is, the five chosen angles of tilt of 40, 30, 20, 10 and $6\frac{1}{2}$ degrees, and the

diagram clearly indicates the balancing of the various parts about the selected points of contact between the rocker and the rocker stand. During the closing movements from an angle of 40 to 20 degrees of tilt the parts are balanced about points in bearing surface 45 and from an angle of 20 degrees to $6\frac{1}{2}$ the various parts are balanced about shoulder 46. When the car has arrived at the $6\frac{1}{2}$ degree position its supporting point 70 remains stationary until the instant of closing and locking the car.

Having thus described my invention what I claim is—

1. In a tilting, side dump car, a body, a 80 rocker thereon, an underframe, a rocker stand thereon adapted to support said body through said rocker, a pivotal point for said rocker on said stand and rolling tooth means to prevent displacement of said rocker when 85 pivoting on said point.

2. In a car adapted to tilt from an upright position to dump its load, an underframe provided with a rocker stand, a tilting body provided with doors hinged thereto and with 90 a rocker supported upon said rocker stand, said stand and rocker cooperating to provide a varying progression of the point of support of said body on said underframe during 95 tilting of the body to and from a dumped position and adapted to maintain said point outside of the perpendicular through the center of gravity of said body and doors during other than upright position of same.

3. In a tilting, side dump car, an underframe, a body, side doors hinged to said body, door operating mechanism connected to said doors and underframe and adapted, as said body is tilted, to cause the door on the lowering side to open and to close as 100 said body returns to upright position, a rocker and a rocker stand between said body and underframe adapted to intermittently delay the progress of the point of contact between 105 said rocker and stand during movement of the body and having their delaying means coordinated with said door operating mechanism.

4. In a tilting body, dump car, a body, a 110 rocker thereon, an underframe, a rocker stand thereon adapted to support said body through said rocker, a tooth on said rocker, a tooth on said stand, an opening in said 115 rocker adapted to receive said stand tooth, an opening in said stand adapted to receive said rocker tooth, a point on said stand, adjacent said stand tooth, adapted to pivotally support said rocker at a point on the latter adjacent said rocker tooth, said teeth being adapted to engage when said point is functioning as described.

5. In a tilting body dump car, a body, a 120 rocker secured thereto, and forming a support for the body, an underframe, a rocker stand forming a part of the underframe and 125

on which said rocker is mounted, said rocker stand having an edge adapted to be engaged by the rocker as the body is tilted and interlocking means provided on the rocker and 5 rocker stand for preventing displacement of the rocker while pivoting on said edge.

6. In a tilting body dump car, a body, a rocker secured thereto and having a curved bearing face flattened at the centerline of 10 the car, an underframe, a rocker stand forming a part of the underframe and on which said rocker is mounted, said stand having a central horizontal portion adapted to be engaged by the central flat portion of the

rocker when the body is upright, and two 15 upwardly and outwardly inclined bearing portions on each side of the central portion and along which the curved face of the rocker is adapted to roll during tilting of the body, and an intermediae portion between the two bearing portions so located as to present a pivoting edge to the rocker, and means for preventing displacement of the rocker while pivoting about said edge.

In testimony whereof, I have hereunto 25 subscribed my name this 26th day of September, 1918.

CHARLES H. CLARK.
